UNITED STATES PATENT OFFICE.

JAMES J. TRACY, JR., OF CLEVELAND, OHIO.

LIQUID-FUEL BURNER

1,111,109.

Specification of Letters Patent. Patented Sept. 22, 1914.

Application filed December 3, 1909. Serial No. 531,126.

To all whom it may concern:

Be it known that I, JAMES J. TRACY, JR., a citizen of the United States, and a resident of Cleveland, county of Cuyahoga, 5 and State of Ohio, have invented a new and useful improvement in Liquid-Fuel Burners, of which the following is a specification, the principle of the invention being herein explained and the best mode 10 in which I have contemplated applying that principle, so as to distinguish it from other inventions.

The present invention, relating as indicated to liquid fuel burners, has regard more 15 particularly to burners for utilizing the heavier hydrocarbon oils, such as kerosene. A large field of use is open for a burner of this type adapted for use on steam automobiles and in various other situations 20 where it is desired to provide a more or less extensive heating area under conditions of combustion quite different from those obtaining in inclosed furnaces and retorts, wherein, I am well advised kerosene and 25 other heavy fuels have been successfully employed.

The object of the invention, then, is the provision of a burner whereby an extended heating zone or area may be obtained just 30 as with a gaseous fuel, or with a liquid one capable of ready vaporization like gasoline.

To the accomplishment of this and related objects, said invention consists of the means hereinafter fully described and particularly pointed out in the claims.

The annexed drawings and the following description set forth in detail certain mechanism embodying the invention, such disclosed means constituting, however, but one 40 of various mechanical forms in which the principle of the invention may be used.

In said annexed drawings:—Figure 1 is a side elevation of a steam generator having associated therewith a burner embodying my several improvements; Fig. 2 is a vertical sectional view of such generator and burner taken on line 2—2, Fig. 3; Fig. 3 is a plan view of the burner with other parts in section, as indicated by the line 45 3—3, Fig. 2; Fig. 4 is a side elevational view of a supplementary burner forming a feature of the invention; Fig. 5 is a sectional view of such supplementary burner on the line 5—5 Fig. 4; Fig. 6 is a front 50 elevation of the same; and Figs. 7 and 8 are side elevations of two different kinds of pilot burners which I utilize along with the foregoing main and supplementary burners.

It has already been indicated that by 60 showing my improved burner in direct association with a steam generator, it is not meant to imply that such association is necessary, nor that other uses for the burner, than to heat such a steam generator, are 65 not available. Accordingly, no more details of the generator's structure are shown than necessary, and the generator coil A is presented in diagrammatic form. It will be understood, however, that the generator 70 is of the flash boiler type, the water entering at the upper end a of the coil and passing out, in the form of superheated steam, at the lower end a'. Such coil is suitably held in an insulating casing A' over the 75 hollow body of the main burner B which is used in the present instance to heat the same. The casing A' is of usual form except that a chamber a² is provided in the upper portion thereof, said chamber communicating at one end a³ with the atmosphere, while at the other end a duct or conduit a⁴ leads downwardly and terminates adjacent to the outer end of the inlet tube b of the main burner body. The top b' of 80 such main burner is in the form of a flat plate resting on the body proper and has a plurality of raised hollow ribs of general circular form wherein are provided a number of closely arranged apertures b², preferably in the form of narrow slits through 85 which the combustible mixture is designed to escape from the burner body and then be ignited. The lower portion of the duct a⁴ fits closely against the outer end of the 90 inlet tube b so as to communicate directly therewith. Such lower duct end, furthermore, is provided with an extension a⁵ into which projects the end of an atomizer 95 or fuel injector C. (See Figs. 1 and 2.) The body of such atomizer receives and 100 supports the ends of two pipes c and c' respectively connected with the steam pipe a' leading from the generator coil A, and with a source of liquid fuel supply, preferably 105 an open tank D wherein the liquid fuel, as kerosene, is kept under simple atmospheric pressure. The inner ends of such two pipes c c', which closely approach each other as shown in Fig. 2, are formed with orifices 110 or nozzles. Thus when steam is admitted to pipe c, it passes with high velocity

across the end of pipe c' , and oil is drawn through the latter pipe by the vacuum thereby caused. Such oil is atomized by the steam jet and then discharged along 5 with the latter across the lower end of the duct a' , through the inlet tube b , and into the hollow burner body B. Incidentally to such discharge of the atomized fuel into the burner body, air in sufficient quantity 10 is drawn through the duct and intermingled therewith to form a proper combustive mixture, which thereupon rises through the apertures in the top of the burner to be ignited. When the apparatus is in operation 15 the air thus supplied to form the combustive mixture, is obviously preheated by its passage through chamber a^2 across the top of the generator, and thus assists in maintaining the fuel in the vaporized state 20 which it is caused to assume by the high temperature of the steam utilized in atomizing the same.

Adjacent to the inlet tube b whereby the combustive mixture is thus admitted into 25 the burner body, but located a trifle above the edge of the burner, I locate a second or supplementary burner E, which preferably takes the form of a flattened nozzle such as illustrated in Figs. 4, 5 and 6. The discharge end of such nozzle is removed some 30 inches from an opening a^3 formed in the generator casing at the point in question, and of considerably larger area than the nozzle, so that as the fuel is discharged 35 from the latter across the top of the main burner B, a sufficient quantity of air is drawn along therewith to render the mixture a combustive one. The construction of this burner is very similar to that of the 40 atomizer provided in connection with the main burner, save that compressed air forced through a pipe e from a second tank D', or other suitable source is utilized therein in place of superheated steam. Oil 45 from the same tank D as that used for the main burner is drawn through a second pipe e' that enters the under side of the nozzle. The discharge end of the nozzle is flattened, spreading out in fan-like form, so as to insure 50 the distribution of the fuel mixture over substantially the entire top of the main burner. Inasmuch as the major portion of the jet of compressed air tends to discharge in a direct line, I make the flattened opening 55 e^2 of the nozzle narrower in the center than at its sides, as clearly appears in Fig. 6, thereby insuring the desired equable distribution of the fuel.

To one side of the opening a^3 through 60 which such secondary burner E discharges into the generator casing, I mount a pilot burner F which may be of any well known form, the ones illustrated in Figs. 7 and 8 being presented as merely typical of several forms of burner available for use in

this connection. Such pilot burner, however, is preferably adapted to utilize the same heavy fuel that is employed in the main and supplementary burners. This may either be supplied under pressure or 70 be drawn in by the effect of the atomizing air jet. In the first case I maintain a small body d of the oil in the lower portion of the compressed air tank D'. The oil thus supplied (through a pipe f') is vaporized in 75 an outer annular chamber f of the burner body F through a central opening f' in which the blast is discharged from the nozzle f^2 . The second pilot burner F' (Fig. 8) has been more especially designed for 80 use in the connection in hand and consists of a shell f^3 , closed at the rear end save for a series of apertures f^4 , into which shell projects an atomizer f^5 as shown. The operation of this atomizer is substantially the 85 same as that of the supplementary burner E, compressed air being supplied thereto through a pipe f^6 , and oil under atmospheric pressure through a pipe f^7 . Such pilot burner, whatever its form is kept 90 lighted during the operation of the apparatus, as need not be explained. Assuming, however, that both the other burners are out, in order to start the apparatus, I first turn on the supply of compressed air 95 to the second or supplementary burner. The blast discharged therefrom is immediately ignited from the pilot burner and quickly causes the formation of sufficient steam in the lower section of the generator 100 coil to permit the atomizer for such main burner to be put in operation. At the same time such second burner also heats the air that passes through chamber a^2 and ducts a' and is then admixed with the atomized 105 fuel.

The general operation of the main burner having been described, it need merely be noted in conclusion that after such burner has been started the supplementary burner 110 is of course turned off. In the course of the normal operation of the apparatus, then, a sufficient head of steam is available, to 115 permit resumption of such main burner's operation at any time, the pilot burner serving to ignite the combustive mixture whenever it is supplied. The apparatus, in other words, provides for the immediate rekindling of the main burner after any reasonable interruption such as may be incident to the usual control, whether automatic or manual, of the supply of fuel to 120 said burner.

While my burner, as should be evident from the foregoing description of its construction and mode of operation, is particularly adaptable for use with a steam generator, it is, of course, not essential that either the hot air or superheated steam for use with the burner be derived from such 125

associated generator, since they may be secured from any suitable source, nor is it essential to the operation of the burner that any heated air be supplied to the inlet tube, since air drawn directly from the atmosphere and at normal atmospheric temperature may be satisfactorily employed. Similarly for the superheated steam any suitable pressure fluid may be utilized, and this also need not be at a high temperature providing preheated air is utilized in connection with the mixture. In other words, it is desirable that either the pressure fluid utilized in atomizing the oil, or else the air utilized in connection with the atomized oil to form a combustive mixture, be at a high temperature, but it is not necessary that both be at such high temperature. By charging the mixture thus formed into a hollow burner body of the familiar type through which the mixture escapes by means of a plurality of small apertures, I am enabled to obtain substantially the same effect as where a gaseous or readily vaporizable fuel is employed, the mixture burning with a clean blue flame, and the whole operation of the burner being noiseless in contradistinction to the operation of burners of the retort type.

When the second type of pilot burner F' is employed, a very considerable advantage is gained over prevailing arrangements, in which, so far as I am aware, such pilot burner has been in the form of a vaporizer utilizing gasoline. This necessitates a separate fuel supply where the main burner is operated with kerosene, or like heavier oil, with attendant annoyance in taking on fuel and possibility of running out of that designed for pilot use, in which event the surplus of heavier oil for the main burner is no longer available.

Other modes of applying the principle of

my invention may be employed instead of the one explained, change being made as 45 regards the mechanism herein disclosed, provided the means stated by any one of the following claims or the equivalent of such stated means be employed.

I therefore particularly point out and 50 distinctly claim as my invention:—

1. A liquid fuel burner, comprising a hollow cylindrical casing forming a combustion chamber, an apertured plate at one end of said casing, a burner body below said 55 apertured plate and forming therewith a mixing chamber, an inlet tube connected laterally to said mixing chamber, an atomizer disposed to discharge into said inlet tube, connections for respectively supplying liquid fuel and superheated steam to 60 said atomizer; a conduit opening laterally into said inlet tube adjacent to said atomizer; and means for heating air and supplying such heated air to said conduit. 65

2. A liquid fuel burner, comprising a hollow cylindrical casing forming a combustion chamber, an apertured plate at one end of said casing, a burner body below said 70 apertured plate and forming therewith a mixing chamber, an inlet tube connected laterally to said mixing chamber, an atomizer disposed to discharge into said inlet tube; connections for respectively supplying liquid fuel and superheated steam to 75 said atomizer; and a conduit closing the end of said casing and forming therewith such combustion chamber, said conduit being connected laterally to said inlet tube.

Signed by me this 30th day of November, 80
1909.
